UNITED STATES PATENT OFFICE.

CARL R. KLOK, OF CHICAGO, ILLINOIS, ASSIGNOR, BY MESNE ASSIGNMENTS, TO
UNITED TABLE-BED COMPANY, A CORPORATION OF VIRGINIA.

TABLE.

1,243,425.

Specification of Letters Patent. Patented Oct. 16, 1917.

Application filed January 16, 1914 Serial No. 812,533

To all whom it may concern: Be it known that I, CARL R. KLOK, a citizen of the United States of America, and resident of Chicago, Cook county, Illinois, have invented a certain new and useful Improvement in Table-Beds, of which the following is a specification.

tion a^6 provided with a pocket a^7 ; the utility of which latter will hereinafter more fully appear.

The bed B comprises a rectangular iron-frame composed of sections b , b^1 and b^2 ; 60 which sections are pivotally connected together by relatively long and short links b^3

The object of my present invention is to provide a novel construction, and arrangement whereby the said carrier frame is movable directly downward from its position within the table, and directly upward to said position, thus obviating the necessity of swinging the two frames over and above the axis of the carrier frame in folding and unfolding the bed, as will hereinafter more fully appear.

It is also an object to provide certain details and combinations tending to increase the general efficiency of a table bed of this particular character.

30 To these and other useful ends, my invention consists in matters hereafter set forth and claimed.

folded. The pivoted legs D support the bed 85 in horizontal position, their upper ends being connected with the links b^3 and b^4 by

35 In the accompanying drawings—
Figure 1. is a side elevation of a table-bed embodying the principles of my invention.

Fig. 3 is a view similar to Fig. 2, but the legs thereof, when folded within the table, form a rectangular bundle.

Fig. 4 is a view similar to Fig. 3 showing the carrier frame swung into position to permit unfolding of the bed.

40 Fig. 4 is a view similar to Fig. 5, showing the bed unfolded. Fig. 5 is a detail section on line 5—5 in Fig. 5. The carrier frame C is drawn into a raised position by a cord or other flexible connection E, secured to the lower end thereof, and running over a ring or other device F, secured to the upper end of the frame C.

As thus illustrated, my invention comprises a table body A having legs a at the

45 prises a table body A , having legs a at the four corners thereof, and having fixed end walls a^1 , as well as a fixed side wall a^2 ; and a bed frame can be swung up and down, fixed top a^3 , whereby a rectangular table with a box-like upper portion is provided. The

50 said top has a hinged section α , and this section, and does not have to be swung up, 105
section is hinged to the removable side walls β ward and over in order to assume the ver-
 α , whereby the top of the table may be vertical position shown in Fig. 3. It will be
opened, in the manner shown in Fig. 3, to be understood that the cord E can be secured
permit folding of the bed. It will also be in any suitable way to keep the carrier
the side wall β has a hinged sec- frame in a raised or horizontal position. 114

seen that the side wall α^2 has a hinged section frame in a raised or horizontal position. 110

In this position, the bed frame is prevented from rotating by the catches *F* on the carrier frame, which engage the section *b*, which may be of any suitable or desired character.

With this construction, the bed is movable about a plurality of parallel axes, one axis being movable about the other. It is thus possible to retain a large portion of the 10 table top in place, as practically only one side of the table is necessarily opened in order to permit unfolding of the table. The pocket *a*⁷ contains the slack portion of the cord *E* when the bed is folded within the 15 table. In this way said cord does not hang in sight when the structure is in use as a table.

With the construction shown and described, therefore, which is designed to solve some of the various problems involved in 20 combining a table with a bed, the table can be of the ordinary size and proportions, such as an ordinary library table, and the bed can be of the proper height and length, 25 and can be of any suitable or desired width. The invention, therefor, involves a novel method of combining these two pieces of furniture in one and the same unitary structure, so that each will have the essential 30 requirements peculiar thereto, to the extent, at least, that the table is of the proper height and is of such width that it may be pushed through an ordinary doorway, and that the bed is of the proper height and 35 length and can be of any suitable or desired width, the table being of any suitable or desired length, depending upon the width desired for the bed. I do not, however, 40 limit myself to the exact construction shown and described.

What I claim as my invention is—

1. A table bed comprising a table body having a movable side, a carrier frame pivoted in the body, movable directly downward from its position in the upper portion of the body, and a folding bed frame rotatively mounted on said carrier frame.

2. A table bed comprising a table body having a movable side, a carrier frame pivoted in the body, movable directly downward from its position in the upper portion of the body, and a folding bed frame rotatively mounted on said carrier frame, said bed frame being horizontal when in use, 55 and also when folded within the table, said carrier frame being horizontal when the bed is folded, but vertical when the bed is in use.

3. A table bed comprising a table body having a movable side, a carrier frame pivoted in the body, movable directly downward from its position in the upper portion of the body, and a folding bed frame rotatively mounted on said carrier frame, 65 said bed frame including pivotally con-

nected sections, one of which sections is swiveled on the carrier frame, and said swiveled section being upside down when the bed is folded within the table.

4. A table bed comprising a table body 70 having a movable side, a carrier frame pivoted in the body, movable directly downward from its position in the upper portion of the body, and a folding bed frame rotatively mounted on said carrier frame, said 75 bed frame being movable about two axes, when folded, one of said axes being fixed and the other axis being movable about the fixed axis.

5. A table bed comprising a table body 80 having a movable side, a carrier frame pivoted in the body, movable directly downward from its position in the upper portion of the body, and a folding bed frame rotatively mounted on said carrier frame, said 85 body supporting said carrier frame in vertical position, when the bed is in use, and means for supporting the carrier frame in horizontal position, when the bed is folded.

6. A table bed comprising a table body 90 having a movable side, a carrier frame pivoted in the body, movable directly downward from its position in the upper portion of the body, and a folding bed frame rotatively mounted on said carrier frame, said bed 95 frame having links which provide space for the mattress when the bed is folded, which links are disposed horizontally when said carrier frame is in lowered position and before the bed-frame is rotated to unfolding 100 position.

7. A table bed comprising a table body having a movable side, a carrier frame pivoted in the body, movable directly downward from its position in the upper portion 105 of the body, and a transversely folding bed frame having an end section thereof rotatively mounted on said carrier frame, said bed frame having folding legs, and being composed of three pivotally connected sections, one section being disposed between the others when the bed is folded, which sections are disposed vertically when said carrier frame is in lowered position and before the bed-frame is rotated to unfolding 110 position.

8. A table bed comprising a table body having a movable side, a carrier frame pivoted in the body, movable directly downward from its position in the upper portion 115 of the body, a folding bed frame rotatively mounted on said carrier frame, and means for swinging the two frames upward within the body.

9. A table bed comprising a table body 125 having a movable side, a carrier frame pivoted in the body, movable directly downward from its position in the upper portion of the body, and a folding bed frame rotatively mounted on said carrier frame, a 130

door at the other side of the body, and means for raising the two frames within the table, accessible through said door.

10. A table bed comprising a table body having a movable side, a carrier frame pivoted in the body, movable directly downward from its position in the upper portion of the body, so that the carrier-frame when swung down will occupy a position between 10 the front legs of the table, a transversely

folding bed frame having an end-section thereof rotatively mounted on said carrier frame, and catches whereby the bed is locked in horizontal position.

Signed by me at Chicago, Illinois, this 15
23rd day of December, 1913.

CARL R. KLOK.
